(57) CLAIM

The ornamental design for a shower sleeve as shown and described.

DESCRIPTION

FIG. 1 is a front perspective view of a shower sleeve in accordance with the present design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the shower sleeve in use. The broken lines illustrate portions of the shower sleeve and form no part of the claimed design.
